UNITED STATES PATENT OFFICE.

PETER KRUSE, OF BROOKLYN, NEW YORK, ASSIGNEE TO E. W. BLISS COMPANY, OF BROOKLYN, NEW YORK.

FLANGING DEVICE FOR SHEET-METAL BLANKS.

1,135,534.

Specification of Letters Patent. Patented Apr. 13, 1915.

Application filed December 31, 1914. Serial No. 879,812.

To all whom it may concern:

Be it known that I, PETER KRUSE, a citizen of the United States, residing at Brooklyn, county of Kings, and State of New York, have invented certain new and useful Improvements in Flanging Devices for Sheet-Metal Blanks, of which the following is a specification.

This invention relates to improvements in the formation of so-called lock joints for sheet metal cans, boxes and similar containers preferably made by automatic can machines and has more particularly for its object, the production of one of the lock joint-forming flanges extending along one edge of the can, etc., blank. This flange is of substantially U-shape having converging shanks and is adapted to be engaged by a hook-shaped flange extending along the opposite edge of the blank whereupon the interhooked flanges are compressed or flattened out to form the desired lap joint. This above mentioned U-shaped flange has hitherto been made in at least two operations and positions of the blank while with the present invention the complete operation is performed in but a single position of the blank, so that the necessary mechanism is simplified and its output increased.

In the accompanying drawing Figure 1 is a cross section of a can flanging device embodying my invention; Fig. 2 is a side view thereof; Fig. 3 a plan view of one of the carriers supporting one of the flange formers; Fig. 4 a cross section on line 4—4, Fig. 3; Fig. 5 a diagrammatic section through the flange-forming elements, showing the still unflanged blank in position; Fig. 6 a similar section showing the blank flanged by the first former; Fig. 7 a similar section showing the free flange-shank bent inward by the second former, and Fig. 8 a top view of a flanged blank bent into shape and showing the lap joint prior to compression.

As shown in Fig. 7, the completed flange is of substantial U-shape, the shanks 10, 11 converging toward each other from the web 12. This web extends at an angle to the plane of blank 13, the latter being more particularly designed for the production of cans or boxes of oblong form as illustrated in Fig. 8. As the longitudinal seam should extend along one of the sharply curved ends 55 of the box the inclined position of the

flange-web facilitates the bending of the blank and insures after such bending, proper symmetry of the seam flange, as may be clearly seen from Fig. 8.

Briefly stated, the means for producing the flange above described comprise a die 14 having a transverse recess or groove 15, the two adjoining perimeters 16 and 17 of which occupy a position corresponding exactly to the mutual location and arrangement of shank 10 and web 12 of the finished flange. The perimeter 18 of groove 15 extends in substantial parallelism with perimeter 16. Die 14 is adapted to perform a slight vertical movement thereby acting as a clamp or pressure bar for firmly holding the blank 13 to a fixed support 19. After the blank has been properly placed upon support 19 in any suitable manner, die 14 is caused to descend in manner hereinafter more fully described, thereby clamping the blank in position. A first former 20 the operative head of which corresponds in outline to that of groove 15, is now advanced in parallelism with the groove sides 16 and 18 until the blank portion 13^a formerly projecting beyond the die (Fig. 5) is forced into groove 15 (Fig. 6). Former 20 is next retracted whereupon a second former 21 movable at an angle to former 20 is advanced to engage the protruding end of shank 11 and thereby turns it inwardly and toward shank 10 until it has assumed the final position illustrated in Fig. 7. This inward bending of shank 11 is facilitated owing to the prior formation of the crease 22 by means of former 20.

The properly timed movements of the above mentioned parts 14, 20 and 21 are brought about as follows:—In the machine frame A, there is journaled a shaft 23 that receives continuous rotary motion in any convenient manner. Upon shaft 23 is firmly mounted a pair of eccentrics 24, 25 adapted to respectively actuate formers 20, 21 and a cam 26 adapted to operate die 14. The latter is carried by the downwardly extending arm 27 of a two-arm lever 28, fulcrumed at 29. The rear arm 30 of this lever is engaged by a fork 31 which is connected through an adjustable rod 32 with another fork 33 straddling shaft 23, fork 33 carrying a cam roller 34 that engages cam 26. It will be seen more particularly from Fig. 1 that the fulcrum 29 of lever 28 is 110

located above and back of the die-groove 15 so that after the completion of the substantially U-shaped blank-flange, the die 14 is not only raised off blank 13 but is also swung forward, *i. e.* laterally away from said flange. In this way the blank is not only released of vertical pressure but is also relieved of any lateral strain to which it may have been subjected while part thereof was drawn into groove 15 by former 20 so that the subsequent removal of the flanged blank is facilitated.

In a suitable inclined guide way 35 of frame A is reciprocably mounted a carrier 36 to which the former 20 is attached by screws 37. Within a suitable recess a carrier 36, there is mounted a slide 38 forced outwardly by a pair of springs 39 that are seated within opposed sockets 40, 41 of carrier 36 and slide 38 respectively. The outward movement of the latter is limited by a nut 42 of a bolt 43 that extends loosely through slide 38 and is tapped into carrier 36 the bolt being fixed in position by a pin 44. Slide 36 is provided with a pair of elongated openings 45 accommodating the knobs 46 of levers 47 carried by a common hub 48 that turns loosely on a shaft 49. Hub 48 is furthermore provided with a forked arm 50 to which is adjustably pivot- 30 ed at 51 one end of a lengthwise regulatable connecting rod 52, the other end of which is attached to the strap 53 of eccentric 24.

As thus far described it will be seen that during each rotation of shaft 23 carrier 36 is once reciprocated whereby the former 20 is first advanced into engagement with recess 15 to form a flange as shown in Fig. 6 and is then retracted. By the interposition of springs 39 between slide 38 and carrier 36 the necessary connection is provided for yieldingly forcing the former 20 into the die-recess.

After former 20 has been retracted, former 21 is advanced to bend the free flange-shank inwardly (Fig. 7), the construction for actuating former 21 being as follows:—In a suitable horizontally extending guide way 54 of frame A is slidably mounted a carrier 55 to which the former 21 is attached by screws 56. Carrier 55 is, by springs 57 yieldingly connected to a slide 58 while the parts 55, 58 are held together by a bolt 59 carrying a nut 60, the construction being a substantial duplicate of the carrier or former 20. Slide 58 is actuated by levers 61 engaging corresponding apertures 62 of the slide and forming part of a hub 63 that turns loosely on a shaft 64. Hub 63 is furthermore provided with an ear 65 to which is fulcrumed at 66 one end of an adjustable rod 67 the other end of which is attached to the strap 68 of eccentric 25.

Simultaneously with the above described formation of the U-shaped flange along one

edge of blank 13, a hook 69, is formed at ^g the opposite edge of the blank the means for performing this operation being not shown as they do not form part of the present invention.

I claim:—

1. A flanging device for sheet metal blanks comprising means for clamping a blank in position, means for forming on said blank a substantially U-shaped flange having a pair of opposed shanks and for subsequently withdrawing a portion of said flange-forming means from the blank, and means for converging said shanks subsequently to the withdrawal of said portion of the flange-forming means from the blank and while the blank is still engaged by the clamping means.

2. A flanging device for sheet metal blanks comprising means for clamping a blank in position, means for forming on said blank a substantially U-shaped flange having a pair of opposed shanks and for subsequently withdrawing a portion of said flange-forming means from the blank, and means for turning one of said shanks toward the other shank subsequently to the withdrawal of said portion of the flange-forming means from the blank and while the blank is still engaged by the clamping means.

3. A flanging device for sheet metal blanks comprising means for clamping a blank in position, means for forming a substantially U-shaped flange along one edge of said blank and, for subsequently withdrawing a portion of said flange-forming means from the blank, said flange comprising a web, a first shank connecting said web to the unbent blank-portion, and a second shank extending in substantial parallelism with the first shank, and means for turning said second shank toward the first shank subsequently to the withdrawal of said portion of the flange-forming means from the blank and while the blank is still engaged by said clamping means.

4. A flanging device for sheet metal blanks comprising means for clamping a blank in position, means for forming a substantially U-shaped flange along one edge of said blank and for subsequently withdrawing a portion of said flange-forming means from the blank, said flange comprising a web that extends at an angle to the plane of the blank, a first shank connecting said web to the unbent blank-portion, and a second shank extending in substantial parallelism with the first shank, and means for turning said second shank toward the first shank subsequently to the withdrawal of said portion of the flange-forming means from the blank and while said blank is still engaged by said clamping means.

5. A flanging device for sheet metal

blanks comprising a die provided with a groove, means for clamping a blank to said die, means for forcing part of said blank into the die-groove to form a substantially U-shaped flange that extends along one edge of the blank and for subsequently withdrawing said last named means from the blank, said flange comprising a web, a first shank connecting said web to the unbent blank-portion, and a second shank that extends in substantial parallelism with the first shank, and means for turning said second shank toward the first shank subsequently to the withdrawal of said blank-forcing means from the blank and while the blank is still clamped to the die.

6. A flanging device for sheet metal blanks, comprising a support, a die adapted to clamp a blank to said support and provided with a groove, means for forcing part of said blank into the die-groove to form a substantially U-shaped flange, that extends along one edge of the blank and for subsequently withdrawing said last named means from the blank, said flange comprising a web, a first shank connecting said web to the unbent blank-portion, and a second shank that extends in substantial parallelism with the first shank, and means for turning said second shank toward the first shank subsequently to the withdrawal of said blank-forcing means from the blank and while said blank is still engaged by the die.

7. A flanging device for sheet metal blanks, comprising a support, a die adapted to clamp a blank to said support and provided with a groove, a first former, means for advancing said former into the die-groove and for withdrawing it therefrom, said advance movement of the first former causing part of said blank to be forced into the die-groove to form a substantially U-shaped flange comprising a web, a first shank connecting said web to the unbent blank-portion, and a second shank extending in substantial parallelism with the first shank, and a second former movable at an angle to the first former and adapted to engage the second shank subsequently to the withdrawal of the first former from the die-groove, thereby turning said second shank toward the first shank while the blank is still engaged by the die.

8. A flanging device for sheet metal blanks comprising a stationary blank-support, a die provided with a groove and adapted to clamp a blank to said support, means for automatically oscillating said die, a slidable first former, means for automatically reciprocating said first former into and out of the die-groove, a second former slidable at an angle to the first former, and means for automatically reciprocating said second former toward and away from the die-groove, either one of said formers being ad-

vanced toward said groove while the other former is retracted therefrom.

9. A flanging device for sheet metal blanks comprising a die provided with a groove, means for holding a blank to said die, a reciprocal first former adapted to force part of said blank into the die-groove to form a substantially U-shaped flange having an outer shank, a reciprocal second former adapted to engage said outer shank, and means for consecutively reciprocating said formers whereby the second former engages said shank after the withdrawal of the first former from the blank.

10. A flanging device for sheet metal blanks comprising a die provided with a groove, means for holding a blank to said die, a reciprocal first former adapted to force part of said blank into the die-groove to form a substantially U-shaped flange having an outer shank, a reciprocal second former adapted to engage said outer shank, a rotary shaft, and a pair of eccentrics fast thereon for consecutively reciprocating said formers whereby the second former engages said shank after the withdrawal of the first former from the die-groove.

11. A flanging device for sheet metal blanks comprising a die provided with a groove, means for holding a blank to said die, a reciprocal yielding first former adapted to force part of said blank into the die-groove to form a substantially U-shaped flange having an outer shank, a reciprocal yielding second former adapted to engage said shank and movable independently of the first former, and means for consecutively reciprocating said formers, whereby the second former engages said shank after the withdrawal of the first former from the blank.

12. A flanging device for sheet metal blanks comprising a die provided with a groove, means for holding a blank to said die, a reciprocal first former adapted to force part of said blank into the die-groove to form a substantially U-shaped flange having an outer shank, a reciprocal second former adapted to engage said outer shank and means for consecutively reciprocating said formers, whereby the second former engages said shank after the withdrawal of the first former from the blank, while both of said formers are withdrawn from the blank during a release of the blank-holding means.

13. A flanging device for sheet metal blanks comprising a stationary blank support, a die provided with a groove and adapted to clamp a blank to said support, a reciprocal first former adapted to force part of said blank into the die-groove to form a substantially U-shaped flange having an outer shank, a reciprocal second former adapted to engage said outer shank subsequently to the withdrawal of the first former

- therefrom, and means for withdrawing the die from the support in a direction extending upwardly from the support and laterally away from the formed blank-flange.
- 5 14. A flanging device for sheet metal blanks comprising a stationary blank support, a die provided with a groove and adapted to clamp a blank to said support, a reciprocal first former adapted to force part 10 of said blank into the die-groove to form a substantially U-shaped flange having an outer shank, a reciprocal second former adapted to engage said outer shank, subse-

quently to the withdrawal of the first former therefrom, and means for withdrawing the die from the support in a direction extending upwardly from the support and laterally away from the formed blank-flange, said withdrawal taking place subsequently to the withdrawal of both of said 20 formers from the blank.
